tion of Maine

Application November 21, 1946, Serial No. 711,282

18 Claims. (Cl. 139—1)

1

This invention pertains to weaving looms, and more particularly to loom frame structures and appurtenant means supported by such structures.

Many looms now used by textile mills are found to be operating at an economic disadvantage to their owners due principally to the relatively low maximum rate of speed at which the looms can be operated. The rate at which a loom may be operated is limited by a plurality of factors, some of the more important of which are the extent or degree of vibration induced in the loom by its several moving parts and the attendant danger of deformation or breakage of parts. Excessive vibration induces abnormally rapid wear of loom parts and usually results in the weaving of a sub-standard quality of cloth. It is desirable that the loom operate at the maximum rate consistent with safety and good weaving, to reduce the cost of weaving each unit of cloth. It is found, however, that when ordinary looms are operated much above their rated speed, excessive vibration occurs, accompanied by poor quality of weaving, rapid wear and deformation of parts, and an excessive number of loom stoppages.

As a result it is generally found to be uneconomical to operate the looms above their rated speed of operation. Efforts have been made to overcome the difficulties encountered in operating looms above their rated speed, but with only indifferent success. For example, it has been proposed to render the loom frame more rigid by attachment of additional girt means extending between the loomsides. These prior efforts were at best only partly successful and did not attain the desired results.

With the above considerations in view, it is an object of the invention to provide means whereby the speed of looms may safely be considerably increased.

It is further an object of the invention to provide means whereby vibration in looms may be considerably reduced even when they are operated at abnormally high speeds.

It also is an object of the invention to provide means accomplishing the above mentioned objects which can equally well be applied to existing looms and incorporated into new looms.

It is another object of the invention to provide a loomside stiffening top girt means so arranged as to transmit crankshaft thrust directly to the stiffened loomsides without deformation of the crankshaft or the loomsides.

It is a further object of the invention to provide a top girt end structure which is so constructed and arranged as to positively maintain

2

the crankshaft bearing boxes at a loomside in permanent alignment.

It is a further object of the invention to provide an improved loom frame including frame reinforcing members providing improved bearing supporting means for movable parts of the loom.

It also is an object of the invention to provide means for stiffening the framework of a loom in critical portions thereof and for reducing vibration incident to loom operation.

The above and other objects which will become evident hereinafter are accomplished by the invention, one preferred embodiment of which is described in connection with the following description and accompanying drawings, of which:

Fig. 1 is a pictorial view of a loom with certain conventional parts removed and portions displaced, with means of the invention applied thereto;

Fig. 2 is a view of a loom frame incorporating means of the invention, as seen from the top of the loom, with certain other conventional parts.

Fig. 3 is a pictorial view of a top girt end according to the invention, showing a fragment of a loomside in outline to illustrate the mode of stiffening the loomside and supporting the top girt end thereon; and buttressing crankshaft bearing boxes.

Fig. 4 is a view showing how the center piece of a top girt is supported by Samson means bearing upon a weave room floor.

Fig. 5 is a view illustrating how diagonal and angle loomside bracing structures according to the invention are secured to a loomside in opposed mutual bracing relationship;

Fig. 6 is a pictorial view of a loom side reinforcing top girt end according to the invention;

Fig. 7 is a plan view of the top girt end shown pictorially in Fig. 6;

Fig. 8 is an end view of the top girt end shown pictorially in Fig. 6;

Fig. 9 is a sectional view along line 9—9 in Fig. 7;

Fig. 10 is a sectional view along line 10—10 in Fig. 7;

Fig. 11 is a view in elevation of the top girt end shown pictorially in Fig. 6, viewed from the inner end thereof;

Fig. 12 is a view showing loom driving means and loom frame bracing support structure for the driving means.

Reference will be made hereinafter to the several drawings, wherein like parts in the several views bear like reference numbers.

A loom to which the several features of the in-

vention apply is shown pictorially in Fig. 1 with the invention applied thereto. The loom framing comprises principally: a right hand loomsid¹e 13, a left hand loomsid¹e 12, a front girt 14, a rear girt 16, a right hand middle girt 18, a left hand middle girt 20, and an arch 33 comprising a right hand arch end 31, a left hand arch end 32 and an arch connection 33. These several frame parts are secured together by conventional means such as bolts and nuts in the usual fashion. The frame members carry conventional weaving instrumentalities or mechanisms, some of which are omitted or but partly illustrated in the interest of clarity. Of the conventional mechanisms shown there may be mentioned the bobbin battery 39 and lay 82 actuated through pitmans 84 by a two-crank crankshaft 86 rotating in outer bearing boxes 47 mounted on the loomsides. The lay is supported for oscillation upon swords 83 interconnected by a hand rail 85. The swords are affixed at their lower ends upon a rocker shaft 87. Below the crankshaft 86 and geared thereto is a camshaft 88 carrying gears and cams including harness treadle cams 93 actuating treadles 92 and also carrying pick cams 94 employed to operate picker means 96.

Crankshaft 86 carries adjacent the loomsid¹e 10 a clutch, brake and gearing mechanism indicated generally by the numeral 100 which is geared to a drive motor means 102 (Fig. 12) and to the cam shaft 88 through gear 104 (Fig. 12). These driving means including the motor are mounted on a base 108. Harness means (not shown) may be supported by arch 30 and actuated by the treadles 92, all in usual manner.

The hereinabove described loom frame and weaving mechanisms are well known and operate in conventional manner and form per se no part of the invention. The loom operates in generally satisfactory manner as long as a relatively low operating speed is maintained. As noted hereinabove, increase operating speed is desirable; but it is found that excessive wear and breakage of parts occurs when the rated loom speed is exceeded. The rocker shaft bearings at the loomsides and other moving surfaces wear excessively due to vibrations set up in the loom which tend to deform many of the parts. In the event of "bang-off" or sudden stoppage of the lay in its forward movement, the crankshaft is often deformed and one or both loomsides broken.

To achieve the abovementioned objects of the invention there are provided means which afford increased stiffness and strength at the loomsides while affording better and more secure bearing surfaces for the critical moving parts, whereby vibration is greatly reduced and objectionable deformation of loom parts is obviated even at much higher than rated loom speed. These means are described hereinafter.

Extending between the loomsides and resting thereupon in a manner hereinafter more particularly pointed out, there is provided a top girt 50 comprising a right hand girt end 52, a left hand girt end 54 and a connector 56. The girt ends 52 and 54 are adjustably interconnected by the connector 56. Connector 56 is attached to the ends by suitable means, as bolts 40 passing through elongated holes in the connector and holes 42 in the girt ends. This adjustability is necessary since it is found in practice that the loomsides are not spaced exactly the same distance apart in all looms of the same model and manufacture. The two girt ends

are of similar construction but of opposite hand. In view of this similarity the description will be limited to the girt end at one loomside. Referring to Figs. 6-11 inclusive the left hand girt end 54 is seen to be comprised of a single rigid piece, preferably in the form of a casting of such thickness in its portions to give the required strength and rigidity. The end comprises a relatively long vertically arranged flange 60 constructed to present an extensive vertically extending surface 61 for abutment against the inner face of the respective loomside. As shown in Figs. 6 and 11, this flange is provided with a plurality of holes, as 62, whereby the end may be securely fastened to the loomside, as by bolts. The end is further provided with a horizontally extending flange 63 which is arranged to overlie and present a horizontally extending surface 63a (Fig. 8) to a portion of the upper surface 13 of the loomside. See Fig. 3. The girt end is also provided with an inwardly and horizontally extending flange 59 which may be used to support any desired conventional warp stop means. When securely fastened to the loomside with the complementary surfaces in close engagement, the girt end is firmly supported against downward movement by the horizontally extending flange, and the loomside is found to be greatly stiffened and strengthened by the action of the vertically extending flange. A reason for preventing downward slippage of the girt end will appear hereinafter.

The girt end is provided with an inwardly extending wing 64 to which the connector 56 is secured as previously noted. Referring to Fig. 6, next adjacent the attaching portion of wing 64 there is provided a series of crankshaft bearing box seat surfaces 65 which are arranged to have seated thereon an inner crankshaft bearing box 44. (See Fig. 3.) The bearing box 44 is secured to the seat surfaces of the girt end by bolts 46. Bearing box 44 includes adjustable thrust screws 45 which are arranged to be adjusted into firm abutting relationship with a bearing box abutment 66 formed on the girt end. Girt end 54, as may be seen from examination of Fig. 6, has a second crankshaft bearing box abutment 48 integral with flange 63, which abutment is arranged to buttress bearing box 47 from rearward slippage (see Fig. 3). To secure bearing box 47 firmly against abutment 48 and against the upper surface 13 of loom side 12, the bearing box is provided with an adjustable thrust screw 49 which is threaded into a tapped hole in the bearing box and is arranged to bear against an upstanding portion 11 of loomsid¹e 12. It should be kept in mind that similar structures and arrangements exist at the opposite side of the loom in connection with top girt end 52 and loomsid¹e 10. As a result of the bearing box abutments buttressing the boxes, rearward thrust of the crankshaft, as when the lay is suddenly stopped in its forward movement, is transmitted through the bearings directly to the girt ends and the loom sides, thus obviating slippage and deformation or breakage of the crankshaft. Additionally the inner bearings obviate undue vibration of the crankshaft. Girt end 54 is provided with a crankshaft well or opening 67 arranged to accommodate the respective crankarm of the crankshaft, and bounded by flange 60, wing 64 and two portions 68 and 69. It will be noted that portion 69 is arranged to transmit crankshaft thrust directly from screws 45 to the adjacent loomside.

Referring to Figs. 1 and 4 it will be seen that the connector 56 interconnecting the top girt ends is utilized as an anchorage for the upper ends of samsons 22, 24, which are secured in bracing relation to middle girts 18 and 20, respectively and which are provided with adjustable feet 26, 28, respectively, which are arranged to rest upon the weave room floor and thus firmly support the middle girts and the samsons. The samsons 22 and 24 thus firmly support the top girt connector 56, and are themselves held in rigid fixation to provide firm supports for intermediate bearings 27, 29 for camshaft 88. Thus vibration and excessive wearing of the camshaft at high speeds is obviated and the loom frame rendered more rigid. The several Samson parts and associated structures are secured together by suitable means, as by bolts as illustrated.

To avoid excessive accumulation of lint thereon, the upper surface of the top girt connector 56 is arched or rounded, as shown more clearly in Fig. 4.

To additionally brace the loom frame against deformation and to reduce vibration, as well as to provide more rigid bearing means for the lay supporting structures, there is provided at each lower front corner of the loom frame, an adjustable articulated diagonal bracket. (See Figs. 1 and 5.) The two brackets are similar but are of opposite hand. Further description will be limited to bracket 71 at the right hand side of the loom, it being kept in mind that a similar and complementary diagonal bracket is at the other side of the loom. Bracket 71 comprises a rear bracket piece 72 suitably secured in adjustable position on the inner face of loomside 10, as by bolts 79, and a front bracket piece 73 secured in adjustable position on front girt 14 as by bolts 78. Adjustability is provided by making the bolt holes in pieces 72 and 73 of elongated form. The two bracket pieces are securely fastened together as by bolts 77 passing through complementary elongated holes in the pieces, whereby the rigid, articulated bracket 71 forms an effectively rigid but adjustable loom frame brace. Bracket piece 73 is provided with a downwardly directed flange 74 to which is adjustably secured as by bolts 77a a rocker shaft bearing bracket 75. (See Fig. 5.) The bearing bracket forms the lower half of a bearing and has attached thereto as by bolts 75a a bearing cap 76. The two pieces in combination form an intermediate bearing for the rocker shaft 87. Together with the usual rockershaft bearing in the adjacent loomside 10, the new bearing effectively eliminates vibration of a respective end of the rocker shaft and excessive wear at the respective rocker shaft bearings.

Abutting against the loomside 10 in opposition to bracket 71 and secured to said loomside by the same bolts 79 is one angle bracket 110 (see Figs. 1, 5, and 12) comprised in structure supporting the drive means base 108. Base 108 supports the previously mentioned drive motor 102 and a bearing 109 in which the clutch end of crankshaft 86 is supported. The base extends outward at right angles to the loomside 10, and in looms of the type toward which the present invention is principally directed, has been supported by a vertical stand extending upwardly from the weave room floor. According to the invention, the base 108 is attached as usual to the loomside, but is otherwise supported by loomside bracing members including the previously mentioned angle bracket 110. This bracket, and opposing diagonal bracket 71 act where the two are bolted to the loomside 10 to effectively strengthen the loomside in that region 75

and act to distribute forces more uniformly throughout the loom frame rather than allowing such forces to be applied in concentration upon restricted portions of the frame. Base 108 is additionally supported at the rear thereof by additional angle brackets 111 and 112 which are secured to the base 108 (Figs. 1 and 12) and which are secured to loomside 10 in opposition to rear girt 16. As more clearly shown in Fig. 1, brackets 111 and 112 are secured to loomside 10 by the same means employed in securing rear girt 16 to that loomside, and act with that girt to materially stiffen the loomside and to more uniformly distribute forces throughout the loom frame.

From the above it will be noted that loomside 10, which is subjected to much greater forces than is the opposite loomside 12, is braced in the region where the driving and clutching forces are applied, by top girt end 52 and base 108. Further the loomside is braced by opposed brackets 110 and 71; and additionally braced by the opposed action of brackets 111, 112 and rear girt 16. The opposing action of the several brackets and girts effectively relieves the loomside 10 from objectionable deformation at much higher than rated loom speeds. The opposite loomside is similarly braced by diagonal bracket 70 and girt end 54. The top girt positively maintains the four crankshaft bearing boxes in alignment, effectively eliminating vibration of the crankshaft and directing crankshaft thrust forces to widely distributed portions of the loomsides. It is found that the loom equipped according to the invention may be operated considerably above rated speed without objectionable vibration; and that the objectionable excessive wear and breakage or deformation of parts is obviated.

It is evident that modifications within the scope of the invention will occur to those skilled in the art, and what I claim and wish to secure by Letters Patent of the United States is:

1. A loom frame comprising loomsides, a front girt, and a back girt, said girts interconnecting the loomsides near the bottom thereof; and top girt means interconnecting the loomsides near the tops thereof, said top girt comprising central section and a detachable top girt end, connecting means between the said top girt and its detachable end, said means comprising a means for longitudinally varying the position of the end relatively to the central section of the girt, and said end being constructed and arranged to abut against and brace against deformation a substantial portion of a loomside and having a horizontal flange portion overlying and resting upon an upper surface of said loomside.

2. For a loom including loomsides, a crankshaft extending between and transversely of the loomsides, and two bearing boxes rotatably supporting each end of the crankshaft; top girt means interconnecting the loomsides and comprising a detachable top girt end, said girt end comprising a loomside stiffening flange with a vertically extending surface to abut against a loom side and a supporting flange with a horizontally extending surface arranged to overlie and rest upon the top of said loomside, said end comprising at least one portion providing a crankshaft bearing box seat for one of said bearings and a bearing abutment for another of said bearings.

3. For a loom including loomsides, a crankshaft extending between and transversely of the loomsides, and bearing boxes rotatably supporting the crankshaft; top girt means interconnecting the loomsides and comprising a detach-

able top girt end, said girt end comprising a loomsides stiffening flange with a vertically extending surface to abut against a loomsides and a supporting flange with a horizontally extending surface arranged to overlie and rest upon the top of said loomsides, said end comprising at least one portion providing a crankshaft bearing box seat and bearing box abutment arranged to absorb crankshaft bearing box thrust.

4. For a loom having a loomsides presenting a vertically extending inner face and a horizontally extending face; a top girt end, said girt end having a long loomsides stiffening flange portion presenting a vertically extending face for abutment against and attachment to said inner face of the loomsides, and having a supporting flange portion with a horizontally extending face for cooperation with said horizontally extending face of the loomsides, whereby the loomsides effectively supports the girt end from vertical slippage and is stiffened by the girt end.

5. In a loom having loomsides and a crankshaft extending transversely of the loomsides; a top girt interconnecting the loomsides and means firmly securing the top girt to the loomsides, said top girt having portions respectively abutting against and overlying and resting upon at least one of the loomsides; crankshaft bearing box structures rotatably supporting said crankshaft; seats on said loomsides and seats on said top girt, each seat supporting a respective one of said bearing box structures; and vertical abutments on said top girt preventing rearward slippage of said bearing box structures under crankshaft thrust.

6. In a loom, first and second loomsides each having a crankshaft bearing box seat thereon, front and rear girts inter-connecting the loomsides near the bottoms thereof, means including a top girt interconnecting and resting upon and bracing respective loomsides and having bearing box seats and bearing box abutments integral therewith, bearing box means one on each of said seats and each engaged with one of said abutments, a two-crank shaft rotatably supported in and by said boxes and prevented from rearward movement by said abutments, a rocker shaft, a lay subject to sudden stoppage mounted on said rocker shaft for oscillatory rocking movement, means operated by the crankshaft to oscillate said lay, first and second diagonal braces interconnecting said front girt with said first and second loomsides respectively and bracing the latter, means securing the diagonal braces to the front girt, bearings one on each of said diagonal braces and rotatably supporting said rocker shaft, means including a middle girt interconnecting said front and rear girts intermediate their ends. Samson means interconnecting said top girt and said middle girt and having an adjustable floor-engaging foot thereon, a drive motor and means gearing the motor to the crankshaft, support means for said motor comprising first and second angle braces, means securing said first angle brace and said first diagonal brace in opposed mutual bracing relationship to a common portion of said first loomsides, means securing said rear girt and said second angle brace in opposed mutual bracing relation to a second common portion of said first loomsides, means securing said second diagonal brace to said second loomsides, and means securing said rear girt to said second loomsides.

7. In a loom having loomsides; front and rear girt means interconnecting the loomsides; means

including a top girt interconnecting said loomsides, said top girt having ends each of which includes an inner and an outer bearing box abutment and an inner bearing box seat, each end further including vertical and horizontal flange means tightly engaging, respectively, an extensive inner and an upper surface of a respective loomsides to brace the loomsides and to support the girt end; inner crankshaft bearing boxes one seated on each top girt end in engagement with an inner bearing box abutment, and outer crankshaft bearing boxes each on a respective loomsides and engaging an outer bearing box abutment of the adjacent top girt end; a two-crank 10 crankshaft rotatably mounted in said bearing boxes with each crank thereof between respective inner and outer bearing boxes; a forwardly and rearwardly moving lay subject to sudden stoppage during forward movements thereof; 15 means operated by said crankshaft to move said lay; means including swords and a rocker shaft movably supporting said lay; loomsides bracing means including diagonal brackets interconnecting respective loomsides with said front girt and 20 movably supporting said rocker shaft; and means securely fastening said top girt ends each to its respective loomsides; whereby said bearing boxes are all positively held in aligned position and rearward thrust exerted thereon by the crankshaft upon sudden stoppage of the lay is transmitted directly through said abutments and to the braced loomsides.

8. In a loom; loomsides and front and rear girt means interconnecting the loomsides; a two-crank crankshaft extending generally between and transversely of the loomsides with each crank thereof positioned near a respective loomsides and inwardly thereof; outer bearing box means one supported on and secured to each 25 loomsides and rotatably receiving said crankshaft; inner bearing box means one positioned near the inner arm of a respective crank of said crankshaft and rotatably receiving the latter; top girt means securely interconnecting the loomsides in the vicinity of the crankshaft and including detachable top girt ends, each of said ends including a bearing box seat supporting a respective inner bearing box thereon and including an extensive vertical flange and a horizontal flange firmly respectively engaging an inner and an upper surface of a loomsides to brace the latter and including an inner and an outer bearing box abutment each buttressing against rearward crankshaft thrust a respective inner and outer crankshaft bearing box and including means for directly transmitting rearward crankshaft thrust from the respective inner bearing box means directly to the braced portion of the respective loomsides.

9. An article of manufacture for strengthening looms, comprising a plural-section top girt including two detachable girt ends; each girt end comprising a portion forming a centrally located well, a bearing box seat and a bearing box abutment at the inner side of said well, a vertical stiffening flange and a horizontal girt end supporting flange at the outer side of said well, and a bearing box abutment integral with said last named flange.

10. For a loom having loomsides, a crankshaft extending between and transversely of the loomsides and a front girt and a back girt connecting said loomsides, a top girt comprising a longitudinal, central section and end members, said end members having vertical and horizontal

flange portions by which they are rigidly attached to the said loomsides, and interconnecting means between said central section and end members comprising longitudinally disposed pads on each, registering openings between the section and end members at the pads, the openings in one pad being elongated to provide for adjustment of an end relatively to the central section, and bolt means passing through the openings for rigidly clamping the central section and ends in position after the ends have been attached to the loomsides.

11. For a loom having loomsides, a crankshaft extending between and transversely of the loomsides, a crank throw at each end thereof, and a front girt and a back girt connecting said loomsides, a top girt comprising a longitudinal, central section and end members, said end members having vertical and horizontal flange portions by which they are rigidly attached to the said loomsides, bearing means at each side of a crank throw, one said bearing means being attached to a loomsides and the other to the adjacent end member of the top girt, and shoulders forming a part of said end members against which said bearing means abut thereby to brace said bearing means against forces imparted thereto by the crankshaft, and interconnecting means between said central section and end members comprising longitudinally disposed pads on each, registering openings between the section and end members at the pads, the openings in one pad being elongated to provide for adjustment of an end relatively to the central section, and bolt means passing through the openings for rigidly clamping the central section and ends in position after the ends have been attached to the loomsides.

12. For a loom having loomsides, a crankshaft extending between and transversely of the loomsides, a crank throw at each end thereof, and a front girt and a back girt connecting said loomsides, a top girt comprising a longitudinal, central section and end portions, said end portions having flanges by which the girt is rigidly attached to the loomsides, bearing means at each side of each crank throw, one said bearing means being attached to the loomsides and the other to the adjacent end portion of the girt, and shoulders formed as an integral part of the end portions of the girt and so positioned that the bearing means abut against them thereby to position the bearings against forces imparted thereto by the crankshaft.

13. Mechanism as defined in claim 12 wherein in one of said bearing means is provided with adjusting means to position it relatively to the cooperating shoulder against which it and the said adjusting means abut.

14. For a loom having loomsides, a crankshaft extending between and transversely of the loomsides, a crank throw at each end thereof, and a front girt and a back girt connecting said loomsides, a top girt comprising a longitudinal, central section and end portions, said end portions each having a vertical flange for abutting against the loomsides to which it is attached and a horizontal flange covering the top of the loomsides

for positioning the girt vertically, and bolt means passing through each of the flanges and the loomsides for securing the girt to the loomsides.

15. For a loom having loomsides, a crankshaft extending between and transversely of the loomsides, a crank throw at each end thereof, and a front girt and a back girt connecting said loomsides, a top girt comprising a longitudinal, central section and end portions, said end portions each having a vertical flange for abutting against the loomsides to which it is attached and a horizontal flange overlying the top of the loomsides for positioning the girt vertically, bolt means passing through each of the flanges and the loomsides for securing the girt to the loomsides, bearings for the crankshaft and pads to which said bearings are attached, one pad being formed as a part of the loomsides and the other as a part of the top girt and positioned so that the bearing attached thereto supports the crankshaft at the opposite side of the throw from that bearing attached to the loomsides, and shoulders comprising an integral part of the girt for bracing the bearings against the reaction of the crankshaft, one for the bearing attached to the girt, and another adjacent the flange overlying the loomsides, for the bearing attached to the loomsides.

16. For a loom having loomsides, a crankshaft extending between and transversely of the loomsides, a crank throw at each end thereof, and a front girt and a back girt connecting said loomsides, a top girt for bracing said loomsides adjacent a point where the crankshaft attaches thereto and a diagonal brace at each side of said loom and connecting means attaching said braces to the front girt at a point spaced from the loomsides and to the loomsides at a point intermediate the point of attachment of the front girt and the top girt to the said loomsides.

17. Mechanism as defined in claim 16 wherein said diagonal braces also have attached thereto a bearing for additionally supporting the rock shaft of the loom.

18. Mechanism as defined in claim 16 wherein one of said loomsides has attached thereto a motor supporting bracket, braces from the lower portion of the loomsides to said bracket, one of said braces being connected to the loomsides by connecting means passing through the loomsides and the diagonal brace adjacent thereto.
